UNITED STATES PATENT OFFICE.

EDWIN LEHMANN, OF PEORIA, ILLINOIS.

DESIGN FOR A BOTTLE.

47,114.

Specification for Design. Patented Mar. 16, 1915.

Application filed November 21, 1914. Serial No. 873,402. Term of patent 7 years.

To all whom it may concern:

Be it known that I, EDWIN LEHMANN, a citizen of the United States, residing at Peoria, in the county of Peoria and State of Illinois, have invented a new, original, and ornamental Design for a Bottle, of which the following is a specification, reference being had to the accompanying drawing, forming part thereof.

The figure is a side elevation of a bottle, showing my new design.

I claim—

The ornamental design for a bottle, as shown.

EDWIN LEHMANN.

Witnesses:

JULIUS MARCUS,
BEN G. ROTH.
